ROLLING MILL

Kurt Rosenbaum, Friedrich Alfred-Hütte, Rheinhausen, Germany, assignor to Fried. Krupp Grusonwerk, Aktien-Gesellschaft, Magdeburg-Buckau, Germany

Application September 11, 1937, Serial No. 163,453
In Germany September 10, 1936.

2 Claims. (Cl. 80—55)

My invention relates to rolling mills of the type having a set of roll driving gear wheels or pinions and one or more sets of working rolls, which are arranged side by side and interconnected by coupling spindles and couplings.

It has been common practice heretofore to erect rolling mills of that type, which are used to advantage in the production of wire and small rods, on bed plates, bases or supporting tracks, 10 on which the standards of the mill carrying the working rolls and the roll driving pinions are adjustably fixed in spaced relation to each other.

However, notwithstanding the fact that the said standards are strongly made and amply proportioned so as to safely withstand the maximum 15 tensile, bending and other stresses, to which they are subjected at work, often a rather high "jumping" of the working rolls occurs, during the roughing and like operations, a drawback, which is 20 due to the heavy shocks re-occurring whenever a fresh piece of work is fed for rapid reduction of its cross section into the passes of the rolls, and which sometimes results in breakage of vital parts of the roller bearings, wherein the working 25 rolls of the mills are journaled.

Another drawback characteristic of rolling mills of the type set forth consists therein, that the proper adjustment of the heavy standards referred to above, the exchange and re-alignment 30 of the rolls and like operations caused by changes in the rolling programme or attendant the replacement of worn out rolls, are rather cumbersome tasks presenting many difficulties known to practitioners, which entail great loss of time 35 and cause a relatively long and undesirable interruption of the work of the rolling mill.

The principal object of this invention is to overcome the said drawbacks and difficulties by providing a structurally improved rolling mill 40 of relatively simple and extremely sturdy construction affording facilities in removing and replacing the rolls.

One of the most important features of the invention consists in the provision of a housing of 45 high rigidity representing at the same time and in one unit a foundation or mill bed and an upright carrier frame, wherein the working rolls and their driving gears are accommodated by 50 means of standards, so designed that they can be more easily displaced, removed and replaced than with rolling mills known heretofore, namely in such manner, that the rolls after having been withdrawn for repair, exchange etc. can be more 55 quickly restored into their proper position with-

out cumbersome aligning, centering, re-adjusting and like time consuming operations.

Other advantages inherent to the improved mill housing consist therein, that its upper section is made in the form of a box, closed at all sides, a 5 structural feature which adds to the rigidity of the housing, more especially since said box section is subdivided by partition walls into a plurality of chambers, and that these chambers can be used to advantage as storage tanks for cooling 10 water and lubricating oil.

Further objects of the invention will become incidentally apparent in the course of the following description to experts in the designing 15 and working of rolling mills.

The nature and scope of this invention are briefly outlined in the appended claims and will be more fully understood from the following specification taken together with the accompanying 20 drawings, in which

Fig. 1 is longitudinal section vertically taken through a rolling mill re-designed according to this invention, and shown by way of an example;

Figs. 2 and 3 are cross sections vertically taken 25 on lines II—II and III—III respectively through the rolling mill shown in Fig. 1;

Fig. 4 is another longitudinal section horizontally taken on line IV—IV through the rolling mill shown in Fig. 1;

Fig. 5 is a longitudinal section vertically taken 30 through a structurally modified rolling mill designed according to this invention, and shown by way of another example;

Figs. 6 to 8 are cross sections vertically taken 35 on lines VI—VI, VII—VII, and VIII—VIII respectively through the rolling mill shown in Fig. 5.

The rolling mill re-designed with the objects in view outlined above and shown in Figs. 1 to 4 comprises:

(1) Gear wheels or pinions 10, 11, 12 of conventional design geared together so as to revolve in opposite directions, of which gear wheel 11 is rotated by a driving wheel 13;

(2) A set of grooved rolls 20, 21, 22 in "three-high" arrangement and in end to end disposition 45 relatively to the gears 10, 11, 12, with which they are cooperatively connected by means of

(3) Universal muff couplings, indicated at 16', 17', 18' and 20', 21', 22', and coupling spindles 30, 31, 32; the latter are yieldingly supported by 50 spindle carriers comprising roller bearings 30', 31', 32', and two armed levers 33, 34, 35;

(4) Standards 41, 42, 43, 44 open at the top, wherein the gear wheels 10, 11, 12 and rolls 20, 55 21, 22 are journaled by means of bearings 24, 55

25, 26, shown in Fig. 3; pressure is applied to the rolls by means of screw spindles 46, 47;

(5) A mill housing, which according to this invention is so designed and proportioned as to 5 jointly enclose and support said standards, rolls, gears, couplings and spindles.

In the embodiment of the invention shown by way of an example in Figs. 1-4 the mill housing is made in the form of a single steel casting, which 10 comprises:

A base or foundation 50, pillars integral therewith designated 51, 51', 51'' in Fig. 4, a rear wall 52 strengthened by ribs 52', 52'', 53', 53'', and a box like hollow upper section 54, which is 15 strengthened by partition walls and subdivided by the latter into a plurality of chambers or tanks i, m, n, o, s adapted for the reception and storage of cooling water and lubricating oil; water and oil are supplied therefrom through conventional 20 distributing means diagrammatically indicated at 58, 58', 59, 59' to the rolls, gears and spindle carriers; the threaded portions of the screw spindles 46, 47 are immersed in and lubricated by the oil contained in chambers i and n; the said chambers are preferably interconnected by channels 25 55, 55', shown in cross section in Figs. 2, and 3 which are made directly in the steel casting; by pumps, not shown, and a system of pipes diagrammatically indicated at 56 water and oil are 30 supplied to the respective chambers.

The cooling water running down over the rolls 20, 21, 22 is discharged through an opening d, provided in the base plate 50, while the lubricating oil overflowing from and passing out of the 35 various bearings concerned is collected in receptacles r, r' formed in the base plate 50 for being re-conditioned and returned by a pump—not shown—into the respective tanks of the upper section of the mill housing.

40 Wide windows are formed between the pillars 51, 51' and 51'', through which the standards 41, 42, 43, 44 are inserted and removed.

Guide elements diagrammatically indicated in Fig. 1 in the form of flat grooves or recesses are 45 provided in the base plate 50 and the upper box section 54 of the mill housing for guiding, accommodating and retaining the standards 41, 42, 43, 44 in proper distance to each other.

After having placed the standards into their 50 working position, the said openings between the pillars 51, 51', 51'' are closed by front plates 57, 57', which are secured in their proper place by screw spindles and nuts designated 60, 60', 61, 61' in Figs. 2 and 4. The standards 41, 42, 43, 44 are 55 in turn fixed in their proper positions by tapering keys 70, screw spindles 71, and nuts 72—as seen in Fig. 3, which is self explanatory.

An opening g in the front plate 57 and another 60 opening h formed in the rear wall 52 of the mill housing in registration with the former allow the material under treatment by the rolls 20, 21, 22 to pass into and out of the rolling mill described.

Another opening in the rear wall usually closed 65 by a lid p and three apertures provided in the pillar 51' (Figs. 4 and 8) render the couplings, spindles and their carriers referred to above readily accessible.

Adjusting means of known design in the form 70 of tapering keys 74, having screw spindles 75 and nuts 76 attached, may be provided to advantage for raising and lowering the working rolls according to working conditions, as seen in Fig. 3, which is otherwise self explanatory.

75 Hooks as indicated at 67 in Fig. 2 may be

formed to advantage at the front plates 57, 57' for facilitating their removal and insertion by means of an overhead travelling crane or other convenient power operated hoisting means.

Various other changes and modifications may 5 be conveniently made in the structural details, assemblage and cooperation of the various component parts of rolling mills of the improved design described above, without substantially departing from the spirit and the salient ideas of 10 this invention.

Rolling mills of the "two-high" type may be likewise re-designed to advantage according to this invention, namely provided with a unitary housing jointly enclosing and supporting all the 15 working rolls, their standards, gears, couplings, and the other accessory parts of the mill.

The rolling mill shown by way of another example in Figs. 5-8 comprises:

(1) Gear wheels or pinions 110, 111, 112 of conventional design geared together so as to revolve in opposite directions, of which gear 111 is keyed to a driving wheel 113;

(2) Two sets of working rolls 120, 121 and 122, 123 in "two-high" arrangement and in end to 25 end disposition relatively to the gear wheels 110, 111, 112; said rolls and gears are cooperatively interconnected by means of

(3) Flexible couplings diagrammatically indicated at 110', 111', 112', 120', 121', 121'', 122', 123' and coupling spindles 130, 131, 132, 133; the latter are yieldingly supported by spindle carriers comprising roller bearings 130', 130'', 131', 131'', 132' and two armed levers 134, 135, 136, 137, 138;

(4) U-shaped standards 140, 141, 142, 143, 144, 145, wherein the bearings indicated at 124, 125 in Fig. 6 and at 126, 127 in Fig. 7 for the aforesaid rolls and gear wheels are slidably mounted; pressure is applied to the working rolls in the 40 usual way by means of screw spindles 146, 147, 148, 149 (Fig. 5);

(5) A mill housing, which comprises:

A base plate of foundation 150; a front wall 45 151; a rear wall 152 strengthened by ribs 153, 153', and a box like upper section 154, which is strengthened by partition walls and subdivided by the latter into a plurality of chambers or tanks i', i'', m', m'', n', n'', o', o'', s', adapted for 50 the reception and storage of cooling water and lubricating oil; water and oil are supplied therefrom through distributing means, diagrammatically indicated at 158, 158', 158'', 159, 159', 160 to the rolls, gears and coupling spindle carriers 55 concerned; the threaded portions of the screw spindles 146, 147, 148, 149 are immersed in and lubricated by the oil contained in chambers i', i'', n', n'', the respective water and oil chambers 60 are interconnected by channels or ducts 154', 155, 156 shown in Figs. 6, 7, 8 which are preferably formed in the steel casting proper; by pumps 65 and a system of pipes—not shown—water and oil is supplied to the respective chambers.

The cooling water running down over the rolls 120, 121, 122 is discharged through openings d', d'', provided in the base plate 150, while the lubricating oil overflowing from and passing out of the various bearings concerned is collected in receptacles t, t', t'' formed in the base plate 150 for being re-conditioned and returned by a pump 70 and pipe lines—not shown—into the respective tanks of the upper section of the mill housing.

Wide windows are formed in the front wall 151, 75

through which the standards 141, 142, 143, 144, 145 are inserted and removed.

Guide elements diagrammatically indicated in Fig. 5 in the form of flat grooves or recesses are provided in the base plate 150 and the upper box section 154 of the mill housing for guiding, accommodating and retaining the standards 141, 142, 143, 144, 145 in proper distance to each other.

After having placed the standards into their working position, the windows in the front wall 151 referred to above are closed by cover plates 157, 157' which are secured in their proper place by screw spindles and nuts designated 160, 160', 161, 161' in Figs. 6 and 7. The standards 141, 142, 143, 144, 145 are in turn fixed in their proper position by tapering keys 170, 170', 171, 171', having screw spindles and nuts attached as seen in Figs. 6 and 7, which are self-explanatory.

Openings *g*', *g*'' in the cover plates 157, 157' and corresponding openings *h*', *h*'' formed in the rear wall 152 of the mill housing in registration with the former, and indicated by dotted lines in Figs. 6 and 7 allow the material under treatment by both sets of working rolls to pass into and out of the rolling mill described.

Another opening *p*' in the rear wall 152 and three narrow apertures provided in the front wall 151 (Fig. 8) render the couplings, spindles and their carriers referred to above readily accessible.

Flanges shown at 9, 9' in Figs. 1, 4 and 5 may be formed to advantage on mill housings of the type described above with the object of providing a very rigid connection between a rolling mill redesigned according to this invention and a similarly designed flanged housing of a kindred rolling mill, or of an additional section to the master mill, of which the rolls are to be driven by those of the master mill through couplings and spindles, indicated in dotted lines at 19, 19', 19'' in Fig. 1 and at 119, 119', 119'' in Fig. 5.

Analogously mill housings of the type described and designed with the objects of this invention outlined above, which may prove in practice too cumbersome, heavy and risky to be cast in one

piece, or too bulky for being machined on the machine tools at disposal of the manufacturer, may be conveniently made in different sections rigidly fixed together by screw bolts and flanges in the manner indicated by the flanged end portions of the mill housings shown in Figs. 1, 4 and 5.

What I claim is:

1. In a rolling mill of the type comprising working rolls superposed upon each other, gear wheels individually revolving said working rolls, standards wherein said rolls and gear wheels are journaled, and coupling spindles cooperatively interconnecting said rolls and gear wheels, an integer mill housing jointly supporting, enclosing and removably retaining said rolls, standards, gear wheels and coupling spindles,—horizontally disposed guide grooves being formed in the mill housing wherein said standards are slidably fixed so as to be capable of being removed from the mill housing in the rolling direction.

2. In a rolling mill of the type comprising working rolls superposed upon each other, gear wheels individually revolving said working rolls, standards wherein said rolls and gear wheels are journaled, and coupling spindles cooperatively interconnecting said rolls and gear wheels, an integer mill housing jointly supporting, enclosing and removably retaining said rolls, standards, gear wheels and coupling spindles,—horizontally disposed guide grooves being formed in the mill housing wherein said standards are slidably fixed so as to be capable of being removed from the mill housing in the rolling direction,—said mill housing having a hollow top portion strengthened by ribs, internally provided in the form of partition walls enclosing a plurality of chambers for the reception of lubricating and cooling liquids, said chambers being disposed in registration with the barrels and necks of the working rolls, with the couplings and coupling spindles and with the necks and teeth of the gear wheels respectively.

KURT ROSENBAUM.
